FREDERICK M. FURBER, OF REVERE, MASSACHUSETTS, ASSIGNEE TO UNITED SHOE MACHINERY COMPANY, OF PATERSON, NEW JERSEY, A CORPORATION OF NEW JERSEY.

BURNISHING-MACHINE.

1,107,282.

Specification of Letters Patent. Patented Aug. 18, 1914.

Application filed November 29, 1909. Serial No. 530,421.

To all whom it may concern:

Be it known that I, FREDERICK M. FURBER, a citizen of the United States, residing at Beachmont, Revere, in the county of Suffolk and State of Massachusetts, have invented certain Improvements in Burnishing-Machines, of which the following description, in connection with the accompanying drawings, is a specification, like reference characters on the drawings indicating like parts in the several figures.

This invention relates to burnishing machines, and particularly to the type of burnishing machines employed in the manufacture of boots and shoes for burnishing the edge of the sole. These machines are frequently termed in the trade "edge setting machines", their operation being known as "setting" the edge of the sole. The present invention is especially concerned with that type of burnishing or edge setting machines in which the tool is given a rapid to-and-fro motion.

The invention has for its object, broadly, to provide a machine of the character indicated which shall be capable of producing a better quality and a greater quantity of work than the machines heretofore used; which shall not be subject to as rapid wear and deterioration as previous machines; and which shall be easier for the workman to use.

The high speeds at which edge setting machines are necessarily operated has resulted, in the constructions heretofore employed, in producing excessive vibration of the entire machine, particularly after the bearing or friction surfaces have become worn. Such vibration is not only objectionable because of the attendant noise, but more particularly, because of the increased strain placed upon the operator. In order properly to burnish the sole edge, the operator must hold the shoe up against the tool with considerable pressure; and it is obvious that excessive vibration of the machine will greatly increase the energy and skill required properly to hold and guide the shoe. It is an important object of this invention to reduce such vibration to a minimum. To this end the mechanism that generates the oscillating motion necessary to operate the tool is placed in the base of the machine frame, and the oscillating motion is transmitted to the

tool at the head of the frame. By this arrangement the heavy rapidly moving parts are located in the position least favorable to the transmission of vibrations to the machine frame. Moreover, these parts are submerged in a body of oil which serves the twofold purpose of directly dampening the vibrations of the frame, and also of reducing the wear of the friction surfaces to a minimum.

In the machines heretofore employed the driving shaft has usually been operated at the rate of about 2500 revolutions per minute; and it has been found impracticable to operate these machines at speeds materially higher for the reason that such speeds result in greatly increased vibration of the entire machine and in very rapid deterioration of the operating mechanism.

Prior edge setting machines of the type in which the tool is given an oscillating motion usually have been arranged to impart only one complete oscillation, or two swings, to the tool, at each revolution of the driving shaft. In these edge setting machines therefore the edge setting iron has been driven at the rate of about 2500 oscillations or 5000 strokes or swings per minute. When it is considered that the chief purpose of the rubbing movement imparted to the edge setting tool is to lay down the nap on the sole edge and to give the surface a smooth hard finish, it will be obvious that the greater the rate of oscillation of the tool, the greater will be the rubbing and polishing action, and consequently the less will be the time required to properly "set" or burnish a given surface.

It is an important object of this invention to provide an edge setting machine in which the operating speed of the tool shall greatly exceed that at which the tools in machines of this character have heretofore been operated. In the form of the invention shown in the drawings this result is obtained by operating a toggle mechanism from a crank pin driven by the main shaft and transmitting the motion of the toggle to the edge setting iron. The arrangement is such that the toggle is straightened and broken twice during each revolution of the shaft. The tool therefore is given two complete oscillations, or four swings, at each revolution of the shaft; and if the shaft is driven at the usual

speed of 2500 revolutions per minute, the tool will make 10,000 swings, or just twice the number made by the tool in the present machines. The rubbing and polishing motion is therefore doubled while maintaining the shaft speed unchanged.

One type of burnishing or edge setting machine in common use is provided with a tool for operating on the forepart of the sole edge and another tool of different shape for operating on the shank portion of the sole edge, both tools being mounted on a carrier that may be locked against movement or may be unlocked and moved to swing the tools into and out of operative position. In using a machine of this type the operator usually starts the burnishing operation at the shank of the shoe near the heel, and when the tool arrives at the juncture of the shank and forepart he unlocks the tool carrier by pressing against it with his hand and then, by giving the carrier a half turn, reverses the position of the tools. The operator next proceeds to set the forepart of the sole edge, and when the tool reaches the juncture of the shank and forepart on the other side of the shoe, the operation of reversing or shifting the tools is repeated. This type of machine is open to the objection that it requires the operator to remove one hand from the shoe every time he shifts the tools. In order to overcome this objection it has been proposed heretofore to reverse the tools by a mechanism operated by a foot or knee lever. But this arrangement is also objectionable since it requires the operator to change his position or balance in order to reverse the tools. The present invention aims to provide a mechanism for moving the tools in and out of operative position, which may be actuated without requiring the operator either to remove his hand from the shoe or to change his position. In the preferred embodiment of the invention the actuating device for this mechanism is located adjacent to the position occupied by a shoe being burnished, and the reversal of the tools is effected merely by giving the actuating device a quick push with the shoe while holding it in both hands.

Another important object of this invention is to provide an edge setting machine with means whereby the edge setting tools are given rapid to-and-fro movements relative to the edge of the sole in different paths appropriate to the varied contours presented by different portions of the sole edge. In setting the shank, for example, it is obviously preferable to have the tool move in a convexly curved path to conform to the concave curve of this portion of the sole edge, but in operating on the forepart, portions of which are straight, it is desirable that the tool shall move in a greater curve or in a rectilinear path. In the embodiment of the present invention illustrated in the accompanying drawings, this result is effected by a mechanism comprising a cam having a plurality of cam faces arranged to engage other cam faces formed on members moving rigidly with the tool holder when it is in either of its operative positions. One pair of cam faces only are in engagement at a time, and the faces are so shaped as to cause the tool to move in the desired path. The machine is provided with shank and forepart tools and the arrangement is preferably such that the shank tool is moved in a convexly curved path when it is in operative position, and the forepart tool is moved in a rectilinear path when it is in operative position, the change in the path of movement of the tools being effected automatically as they are shifted in the manner hereinabove described.

It is customary to provide edge setting machines with a finger hook or finger rest rigidly secured to the frame of the machine and extending outwardly into a position adjacent the edge setting iron so that it may be grasped conveniently by the operator and aid him in guiding the shoe as he burnishes the toe portion of the sole. In burnishing the shank portion, however, it is frequently the case that the heel of the shoe strikes the finger rest as the tool approaches the heel and thus interferes with the setting of the edge close to the heel. With some kinds of heels this interference is not especially serious as the operator can tip the shoe sufficiently to allow the tool to operate close to the heel. This tilting movement, however, throws the sole edge out of proper engagement with the tool. On high heeled shoes and shoes having heels that are pitched forward the finger hook effectually prevents the burnishing of that portion of the edge close to the heel, and if this portion of the edge is to be burnished on the edge setting machine, it must be done at a later operation after the finger rest has been removed. The present invention aims to provide a construction whereby the difficulty above described may be avoided; and to this end the finger hook is so arranged that it may be readily locked against movement, or unlocked and permitted to move. This operation is preferably effected automatically by the shifting of the tools, and the construction is such that the finger hook is locked when the forepart tool is in operative position, but is unlocked and free to move when the shank tool is in operative position. By this arrangement, when the heel of the shoe strikes the finger hook during the burnishing of the shank, the hook merely moves with the heel and therefore permits the operation of the shank tool clear up to the heel. The invention also comprises other features, including certain details of construction.

tion and combinations and arrangements of parts, which will be later described and claimed.

In the accompanying drawings, Figure 1 is a front elevation of an edge setting machine constructed according to the present invention; Fig. 2 is a side elevation of the mechanism at the head of the machine, certain of the parts being broken away; Fig. 3 is a front elevation of the tool holder and the adjacent parts; Fig. 4 is a cross sectional view taken on the line 4—4 Fig. 2, showing in elevation the arm that supports the finger hook; Fig. 5 is a cross sectional view showing certain details of construction that will be referred to later; Fig. 6 is a perspective view of the toggle and transmitting mechanisms; Fig. 7 is a cross sectional view taken on the line 7—7 Fig. 2 showing one pair of coöperating cam surfaces for controlling the path of oscillation of the tool; and Fig. 8 is a cross sectional view taken on the line 8—8 Fig. 2 showing another pair of cam surfaces.

Referring now to the drawings, 2 indicates the frame that supports the operating parts of the machine and in which certain of the parts are concealed. As before stated, the mechanism for generating the oscillating or to-and-fro motion necessary to operate the edge setting tool is located in the base of the machine. This mechanism comprises a shaft 4 supported in suitable bearings and driven in any convenient manner as by a belt running on fast and loose pulleys, one of which is indicated in the drawings at 6. A belt shifter 8 may be employed to start and stop the machine. Inside the frame the shaft is provided with a disk 9 preferably formed integral with the shaft and a crank pin 10 projects rigidly from said disk. The crank pin is rotatable in a block 12 which is slidably mounted in a slot or slideway 14 formed in one end of a lever 16, the lever being pivoted on a stationary stud 18 projecting from the frame. The other end of the lever 16 is pivotally connected by a pin 20 to a link 22, which in turn is connected by a pivot pin 24 to an arm 26 of a bell crank lever 28. The bell crank is rigidly secured to a rockshaft 30 supported by bearings for ed in the machine frame. The lever 16 and link 22 constitute the toggle mechanism above referred to. In Fig. 1 the toggle is shown in its straightened condition and the arm 32 of the bell crank 28 is in its uppermost position. It will be clear that if the shaft 4 is rotated through an angle of 90° the lever 16 will be moved about its pivot 18 to its extreme inclined position, and the arm 32 of the bell crank will be moved to its lowermost position. If the shaft is now rotated 90° more, the members 16, 22 and 32 will be returned to exactly the positions in which they are shown in Fig. 1. A further

rotation of 90° will move the lever 16 into its extreme inclined position in the opposite direction to that previously occupied, and will again cause the arm 32 to be moved to its lowermost position; and if the shaft is given a still further rotation of 90°, all of the parts will be moved back to the positions in which they appear in Fig. 1. A single complete rotation of the shaft 4 therefore causes the arm 32 to make two complete oscillations or four distinct strokes or swings. If therefore the shaft is rotated at a speed of 2500 revolutions per minute the arm 32 will make 10,000 strokes.

The base of the machine is filled with lubricating oil up to a height sufficient to submerge all the friction surfaces, the oil level being indicated by the dotted line in Fig. 1. All of the parts just described are therefore submerged in oil and are maintained in their most efficient operating condition. This large body of oil in the base of the machine also exerts a dampening action on the vibrations of the machine frame, in the same manner that the vibrations of a tuning fork are damped when it is thrust into a body of oil or other liquid. The oil may be drawn off by removing a threaded plug 33; and a removable plate 35 is provided to permit access to the toggle mechanism for making repairs or renewals.

The oscillating motion generated by the mechanism above described is transmitted to a rockshaft 34, supported in bearings at the head of the frame 2, and through said shaft to the burnishing tools. This transmission is effected by means of a short arm 36, rigidly secured to the rockshaft 34 as by a pin 38, and a reciprocating rod 40 having its ends connected to the arms 32 and 36. In order to avoid the use of friction surfaces in the transmitting mechanism, the rod 40 is connected to the arms 32 and 36 by two joints or connections of novel construction designated in the drawings by the numeral 42. Each of these joints consists of two pairs of clamping plates 44 and 46 respectively between which are secured a plurality of short pieces of hardened wire 48 such, for example, as piano wire. The plates are clamped securely onto the wires by bolts 50. While the arm 32 oscillates in an arc, so short that it is substantially a straight line, its effective component being exerted in the direction of the axis of the rod 40, still there is also a slight ineffective component exerted in a direction substantially perpendicular to said rod. This is also true of the arm 36 as it oscillates about the axis of the shaft 34. The distance between the clamps 44 and 46 is very short; and the wires 48 are sufficiently stiff to transmit the reciprocating movements imparted to these members by the bell crank 28, but at the same time are sufficiently flexible to permit the slight

lateral movements of the members 32 and 36 as they oscillate about the axes of their respective shafts 30 and 34. This joint has special advantages in the present machine, 5 since it avoids the employment of joints having friction surfaces which would soon wear sufficiently to cause an appreciable amount of lost motion. Any lost motion in the transmitting mechanism is, of course, 10 greatly multiplied at the tool, and such lost motion rapidly increases with continued operation of the machine and results in increased wear of other parts of the mechanism and in excessive vibration of the entire 15 machine frame. The joint above described avoids all of these difficulties, requires no lubrication or attention and is cheaper in first cost and in renewals than the usual joints. Furthermore, since these joints take 20 up the slight lateral component of motion of the parts 32 and 36, they prevent the lateral vibration of the rod 40 that otherwise would be produced.

The high speeds at which this machine is 25 operated make it desirable to have the moving parts as light in weight as is consistent with the requisite strength. For this reason, I prefer to use an aluminum tube for the reciprocating rod 40; and as aluminum is 30 comparatively soft and therefore does not hold screw threads or pins well, I have devised a novel connection shown in Fig. 5 for securing the ends of the tube 40 to the clamp members 46. This connection comprises a 35 strong collar 52, having bulged or inferiorly concaved walls, and a plug having an internally screw-threaded shank 53 and an expansible body portion 54, the sides of the body portion being convexly curved to correspond 40 in shape to the concaved curve of the interior walls of the collar. Two saw cuts are made through the body portion at right angles to each other to give this portion flexibility. The body 54 is also provided 45 with an axial tapered bore in which is received a tapered expanding member 56 having a screw threaded stem portion 58 which engages in the threaded shank 53. The collar 52 is placed over the end of the 50 tube 40 and the body 54 of the plug is inserted in the end of the tube. As the expanding member 56 is forced inwardly by threading the stem 58 into the shank 53 the sections of the plug are spread apart and 55 expand the end of the tube into the bulged portion of the collar thus securing the tube rigidly between the plug and the collar.

When the machine is running at high 60 speeds there is some tendency for the reciprocating rod 40 to spring near its middle portion, particularly if it is very long; and unless this tendency is resisted the vibration thus set up, or as it is sometimes termed "whipping," may become sufficiently serious 65 to break or bend the rod. Trouble from

this cause is effectually prevented by securing a spring 60 to the rod near its middle by means of a clamp 62 and having the spring project through an aperture in the frame and bent over to form a loop with its end secured to the frame as indicated in Fig. 1. The spring yieldingly resists any tendency of the rod to vibrate laterally but does not interfere with the reciprocating movements of the rod. This arrangement is preferable 70 to a sliding bearing or a stationary guide 75 since it absorbs no energy.

As indicated in Fig. 2 the machine is of the twin type and the mechanism at one end only of the head of the machine will 80 be described, it being understood that this mechanism is duplicated at the opposite end.

By the mechanism above described a rapid rocking motion is imparted to the rockshaft 34. This rockshaft extends entirely across the head of the machine and is provided at its end with a downwardly inclined portion 64. A groove 66 is formed in the rockshaft, as shown in Figs. 2 and 6, for the reception of a rocker frame 68 of peculiar form. The rocker frame is pivoted to the shaft 34 by a pin 70, and a strong leaf spring 74 is interposed between the bottom of the groove 66 and the rocker frame 68. The forward end of the rocker frame has a vertical bore formed therein in which is received a cylindrical sleeve 76 having an integral plate-like head 78 which rests upon the upper end of the bored portion of the rocker frame. The tool holder 80 has a long stem 82 the upper portion of which is square and projects through a correspondingly shaped hole in the head 78 so that the sleeve and tool holder have a constant angular relationship. The tool holder carries removable burnishing tools 84 and 86 of usual form and has an inclined locking portion shaped to engage in a locking jaw 88 formed on the lower end of the forward portion of the 90 rocker frame, as is best shown in Fig. 3. A spring 90 interposed between a shoulder on the stem 82 and another shoulder formed inside the rocker frame tends to maintain the tool holder in its raised or locking position. 95

In Fig. 2 the shank tool 86 is shown in operative position and the forepart tool 84 in inoperative position. The mechanism for shifting or reversing the tools comprises 100 an actuating lever 92 pivoted to the frame at 93 and having a plate 94 located adjacent the position occupied by the shoe being burnished. The plate 94 may be angularly adjusted on the lever 92 and secured in adjusted position by a bolt 96. A spring 98 holds the lever yieldingly in the position shown in Fig. 2. The actuating device 92 is also provided with an extension 100 projecting into a position above 110

the stem 82. The forward end of said extension is forked and carries a block 102 mounted between the fork members on pivot screws 104. Said block has an aperture formed therethrough in the walls of which is cut a square female screw thread of long pitch; and a bolt 106 having a corresponding male thread is received in said aperture. The block 102 and bolt 106 thus form 10 coöperating cam members. The upper end of the cam bolt 106 has an enlargement 108 formed thereon which prevents the bolt from dropping through the cam block and also operates by having the greater portion 15 of its weight disposed on the left hand side of the axis of the bolt, as seen in Fig. 2, to keep the block tipped in the position shown in said figure. The lower end 110 of the cam bolt 106 is reduced in size and 20 squared to enter a square hole 112 formed in the upper end of the tool holder stem 82. The operation of the reversing mechanism is as follows:—Suppose the operator to be burnishing the shank of a shoe on the 25 tool 86; when the tool arrives at the junction of the shank and forepart the operator gives the plate 94 a quick thrust with the shoe directly away from him while still holding it in both hands. This movement 30 rocks the lever 92 on the pin 93 and swings the cam block 102 downwardly in the arc of a circle. The threads of the cam block acting on the threads of the cam bolt 106 tend to rotate said bolt and through 35 the connections 110 and 112 to rotate the stem 82 and tool holder 80. The locking jaw 88, however, locks the tool holder against such rotative movement. The first result of swinging the lever 92 40 therefore is to move the holder 80 downwardly against the tension of the spring 90 till it disengages the locking jaw 88. The instant this disengagement takes place the tool holder is rotated by the cam members 102 and 106 through an angle of 180° 45 thus bringing the forepart tool 84 into operative position. The spring 90 acts immediately upon the arrival of the holder 80 into locking relation to the jaw 88 to 50 raise the holder and lock it against rotation as before. In practice the reversal of the tools is effected instantaneously. The edge of the shoe sole is normally presented to the operation of the edge setting tools 55 with the sole in substantially a vertical plane, and the actuating device for the tool shifting mechanism is located behind and closely adjacent to the position occupied by the sole of the shoe being burnished so 60 that, while it is out of contact with the shoe during the burnishing operation, still it is in the position most convenient for operation by the workman, and requires him neither to remove his hand from the 65 shoe nor to change his position in front

of the machine. Should the operator push against the finger hook with the shoe instead of against the plate 94 he would still effect the reversal of the tools exactly as before; and it is contemplated that the reversing mechanism may be actuated by 70 striking the finger hook with the shoe instead of by striking the plate 94. Coöperating stops 111 and 113 disposed respectively on the actuating lever and frame 75 limit the movement of the lever about its pivot.

As previously stated, it is preferable to have the shank tool oscillate in a curved path and the forepart tool oscillate in a rectilinear path. In order to effect this result a cam bar 114 is pivoted to the frame at 80 116 and is provided at its forward end with a downwardly inclined portion having a flat cam face 118 and a curved cam face 120. 85 The bar 114 is normally stationary, but can yield against the action of a strong spring 122 surrounding a bolt 124 projecting from a portion of the frame. The tension of said spring may be adjusted by a hand nut 126. 90 The rocker frame 68 is provided with a curved cam face 128. In the positions in which the parts are shown in Fig. 2 the cam face 120 is engaged by a portion of the sleeve head 78 which is thick enough to hold 95 the cam faces 118 and 128 out of contact with each other. This portion of the head 78 has a plane upper surface that forms a coöperating cam face for the face 120. The member 78 is, therefore, for the purposes of 100 this mechanism, a cam plate. The rock-shaft 34, frame 68, plate 78, tool holder 80 and the tools 84 and 86 are all locked rigidly together for oscillating movement. The spring 74 holds the rocker frame up- 105 wardly so that as the rocker frame and plate 78 are oscillated the flat surface of the plate is at all times held in engagement with the curved cam face 120. Consequently while the parts are in this relation 110 the shank tool 86 is caused to oscillate in a curved path. If the tools are now reversed by the mechanism above described, the portion of the plate 78 previously in engagement with the cam face 120 will be swung 115 out of engagement with said face and a thinner portion 129 of said plate will be moved into the position opposite the cam 120. The spring 74 now operates to force the cam face 128 on the rocker frame into 120 contact with the plane surface 118 on the cam bar 114. The cam face 128 has the form of a portion of a cylindrical surface the axis of which passes through the burnishing face of the forepart tool. As the 125 surface 128 is rocked in contact with the surface 118 the axis of the surface 128, and therefore the burnishing face of the forepart tool, will always remain at a constant 130 distance from the face 118, and as the face

118 is a plane surface the forepart tool will oscillate in a rectilinear path.

By the above described mechanism the path of travel of the tools is changed automatically as one tool or the other is thrown into operative position. The mechanism is very simple in construction and as the cam faces merely have a rocking or rolling engagement with each other, the wear 10 of these parts is practically negligible.

The spring 122 is provided for the purpose of enabling the tools to yield against the pressure of the work; and the spring is made adjustable so that its tension may 15 be varied to suit the character of the work. It is obvious that it is necessary to hold a heavy thick-soled shoe up against the tool with much greater pressure, in order to burnish the edge properly, than is necessary in 20 burnishing a light thin-soled shoe, such as a woman's shoe. The adjustment of the spring here provided permits the operator to vary the pressure to meet the requirements of the different kinds of shoes.

25 The finger rest or hook 130 is provided with a gas passage 132 and a burner tip 134, thus constituting a combined finger hook and gas burner. A plurality of grooves 136 are formed in the rear end of 30 said hook to facilitate its connection by means of tubing 138 with a controlling cock 140. The hook 130 is longitudinally adjustable in a supporting arm 144 so that it may be positioned properly with reference to the 35 burnishing irons. A pin 146 pivotally supports the arm 144 on the actuating lever 92 and an aperture 148 is formed in said lever through which the finger hook extends and in which it may have a limited swinging 40 movement about the pivot 146. The finger hook is grasped by the workman as he burnishes the toe portion of the sole and aids him in guiding the shoe properly during operation on this portion of the shoe. It is necessary therefore that the hook shall be locked 45 against movement during this operation. For this purpose the arm 144 is provided with an inclined slot 150 having vertical shoulders 152 formed in the walls of the 50 slot and a locking plate 158 extends through the slot and cooperates with the shoulders in a manner presently to be described. The plate 158 has a cylindrical shank portion 154 which is received in a correspondingly 55 shaped recess formed in the lever 92 and a spiral spring 156 is interposed between the bottom of the recess and the end of the shank and operates to press a collar 157 rigid with the shank into frictional engagement with a portion of the lever 92.

60 It will be clear that when the locking plate occupies the position in which it is shown in full lines in Figs. 2 and 4, the arm 144 and therefore the finger hook is unlocked and free to move. But if the plate

is tilted about the axis of the shank 154 into the position indicated in dotted lines in Fig. 4 the arm 144 will then be locked by the engagement of the plate 158 with the locking shoulders 152. The position of the locking plate in the slot is controlled by two projections 160 and 162 provided respectively on opposite ends of the tool holder 80. It should be noted that the projection 160 is in a lower plane than the projection 162, and 75 that the former is on the end of the holder that carries the forepart tool while the latter is on the end that carries the shank tool. When the shank tool is in operative position therefore the projection 160 is in contact with the plate 158 and holds it in its tilted or ineffective position. The finger hook at this time is therefore free to move when the heel of the shoe strikes it during the burnishing of the shank. In order to substitute the forepart tool for the shank tool the actuating lever 92 is swung downwardly as previously described and this movement carries the locking plate away from the projection 160. The tool holder is then rotated into its reversed position and as the lever 92 is returned to its normal position by the spring 98 the right hand side of the plate 158, as seen in Fig. 4, will contact with the projection 162 and be tipped into the position indicated by the dotted lines in said figure. The arm 144 and finger hook 130 are now locked against movement. When the shank tool is again swung into operative position the projection 160 will tip the plate 158 back into 80 its inclined position.

Having described my invention what I claim as new and desire to secure by Letters Patent of the United States is:

1. A machine of the class described having a machine frame, an edge setting tool arranged near the head of said frame and means for operating said tool, said means comprising mechanism located in the base of said frame for generating rapid to and fro movements, and mechanism including an upright rod arranged to reciprocate in substantially a straight line for transmitting said movements to said tool. 105

2. A machine of the class described comprising in combination a machine frame, a rock shaft arranged at the head of said frame, a burnishing tool operated from said rock shaft, mechanism located in the base of the frame for producing rapid to-and-fro movements, means including a reciprocating rod for transmitting motion from said mechanism to said rock shaft and means for preventing the lateral vibration of said rod. 110

3. A machine of the class described comprising in combination a machine frame, a burnishing tool, means including a reciprocating rod for imparting rapid to-and-fro movements to said tool, a clamp secured to said rod near its middle, and a looped spring 120 125 130

having one end extending through an aperture in the machine frame and secured to said clamp and the other end secured to the side of the frame opposite the rod, the 5 looped portions of the spring being arranged to bear against the frame, whereby lateral vibration of the rod is prevented.

4. A machine of the class described comprising, in combination, a machine frame, a 10 rock shaft supported thereby near the head of said frame, a burnishing tool connected with said rock shaft to be driven thereby, a drive shaft in the base of the frame, a toggle mechanism operated by said drive shaft and 15 driving connections between said mechanism and said rock shaft, said connections including a reciprocating rod and a joint at each end of said rod arranged to permit slight lateral movements of the rod relatively to the parts connected thereto.

5. A machine of the class described comprising in combination a rotary shaft, a crank pin secured to said shaft, a block rotatable on said pin, a toggle lever having a 25 slideway in which said block is received, a toggle link pivotally connected to said lever, a rock shaft operatively connected with said toggle mechanism and a burnishing tool operated from said rock shaft.

6. A machine of the class described comprising in combination, a machine frame, a rotary driving shaft, a crank pin secured to said shaft, a block rotatably mounted on said pin, a toggle lever pivoted intermediate 35 its ends and having a slideway formed in one end in which said block is received, a toggle link pivotally connected to the other end of said lever, a bell crank lever having one arm pivotally connected to said link, all 40 of said parts being arranged in the base of the machine frame and submerged in oil, a rock shaft arranged at the head of said frame, an arm rigidly secured to said rock shaft, a reciprocating rod having its ends connected respectively to said arm and to the other arm of said bell crank lever, such connection at each end of the rod being effected through a joint comprising two clamping devices and a plurality of short sections of hardened wire connecting said devices and having their ends rigidly secured by said clamping devices, and a burnishing tool operated from said rock shaft.

7. A burnishing machine comprising in 55 combination, a burnishing tool and means for imparting rapid to-and-fro movements to said tool, said means including a joint comprising two clamping devices and a connecting member secured between said clamping devices, said member being composed of a plurality of hardened wires.

8. A burnishing machine comprising, in combination, a rocker frame, a tool holder, a plurality of edge burnishing tools carried 60 by said tool holder, said holder being mount-

ed to rock with but arranged to have a rotative movement relatively to said frame, and means for positively effecting a step by step rotation of said tool holder, said means including a device located in close proximity to and opposite the tread face of the sole of the shoe when in burnishing position and arranged to be operated by movement of the shoe being burnished to actuate said means.

9. A burnishing machine, comprising in combination, a rocker frame, a tool holder, a plurality of tools carried thereby, said holder being mounted to rock with said frame and arranged to have a rotative movement relatively thereto to shift said tools, means for locking said tool holder against said rotative movement, an actuating lever, and connections between said lever and tool holder whereby the actuation of the lever effects a rotative movement of said tool holder relatively to said rocker frame, said lever having a part located adjacent to the position occupied by the shoe when in burnishing position to enable the workman, while holding the shoe firmly in both hands and while standing in the position that he normally occupies while burnishing the shoe, to operate said lever by moving the shoe against it and thereby to shift the tools carried by said tool holder.

10. A machine of the class described comprising in combination a rocker frame, a tool holder arranged to interlock with said frame, means for positively moving one of said members to unlock said holder and means for changing the angular relation of said frame and holder to each other.

11. A machine of the class described comprising in combination a rocker frame, a tool holder rocking with but movable relative to said frame into different operative positions, and means for positively moving said holder from one operative position to another, said frame and holder being arranged to interlock with each other when in certain positions.

12. A machine of the class described comprising in combination a rock shaft, a tool holder rocked by said shaft but arranged for movement relatively thereto about an axis, means for locking said holder against the latter movement, a plurality of tools carried by said holder, and manually operated mechanism including a pair of devices in frictional engagement with each other for effecting first an unlocking movement and thereafter a pivotal movement of said tool holder to move one tool out of and another into operative position.

13. A burnishing machine comprising in combination a rocker frame, a tool holder rotatable thereon, means for locking said holder against rotation relatively to said frame, an actuating device located close to the position occupied by the sole of the shoe

- when in burnishing position and arranged to be operated by the shoe being burnished by a bodily movement of the shoe out of burnishing position and into engagement with said device, and means intermediate said device and tool holder arranged to transmit the motion of said actuator to said holder to interrupt said locking connection and to rotate the holder.
14. A machine of the class described, comprising in combination, a rocker frame, a tool holder rotatable thereon, a plurality of edge setting tools carried by said holder, means for locking said holder against rotation relatively to said frame, and positively acting mechanism for unlocking said holder and for rotating said holder to shift the tools, said mechanism comprising an actuating device located close to and opposite the position occupied by the tread face of the sole of the shoe when in burnishing position and so positioned with relation to the adjacent parts of the machine as to afford an unobstructed path for a direct bodily movement of the shoe against said device to operate said mechanism.
15. A machine of the class described comprising in combination a rocker frame, a tool holder, means for locking said holder against angular movement relatively to said frame and positively acting means for unlocking said holder from said frame and for thereafter effecting a positive angular movement of said holder relatively to the frame.
16. A burnishing machine having a plurality of burnishing tools mounted for movement toward and from a specified point, in combination with mechanism for moving said tools toward and from said point, said mechanism including an actuating device out of contact with the shoe during the burnishing operation but located close to the position occupied by the tread face of the sole of the shoe being burnished and arranged to be operated by a bodily movement of the shoe out of burnishing position and into engagement with said device.
17. A machine of the class described comprising in combination a rocker frame, a tool holder rotatable thereon, an operating lever pivoted to the frame of the machine, a member arranged to engage loosely the tool holder and a second member carried by the operating lever and co-operating with the first member to rotate said holder.
18. A machine of the class described comprising in combination a rocker frame, a tool holder rotatable thereon, said frame and holder being arranged to interlock directly with each other, means for yieldingly holding said members in their interlocking relation, an actuating lever pivoted to the frame of the machine, means for yieldingly holding said lever in position to be actuated, co-operating stops for limiting the movement of said lever, a block pivotally mounted on said lever and having a threaded aperture formed therethrough, and a threaded bolt extending through said aperture and arranged to loosely engage a stem projecting from the tool holder, whereby when said lever is actuated the tool holder is unlocked from said frame and is rotated relative to the frame.
19. A burnishing machine comprising a horizontal rock shaft having a downwardly inclined end portion, said shaft being provided with a deep groove extending backwardly from the end of the shaft, a rocker frame positioned in said groove and a tool holder operatively associated with said rocker frame.
20. A burnishing machine having in combination a burnishing tool and means including a yielding cam for imparting to said tool rapid to-and-fro movements in a rectilinear path.
21. A burnishing machine having in combination, a burnishing tool, mechanism for imparting to said tool rapid to-and-fro movements and means including a yieldingly supported cam for controlling the path of movement of the tool.
22. A burnishing machine having, in combination, a burnishing tool, means for moving the tool, mechanism for causing said tool to move in a predetermined path, said mechanism comprising a cam and a member rigid with the tool engaging said cam, and an adjustable spring bearing on said cam.
23. A burnishing machine having, in combination, a tool holder movable into different operative positions, means for vibrating said holder in a curved path when it is in one position and means for vibrating said holder in a substantially rectilinear path when it is in another position, the last mentioned means including a yieldingly supported cam plate.
24. A burnishing machine having, in combination, a tool holder, a plurality of tools supported on said holder in fixed relation to each other, means for moving said tools in and out of operative position, means for causing one of said tools to be vibrated in a curved path when it is in operative position and means for causing another tool to be vibrated in a substantially rectilinear path when it is in operative position.
25. A burnishing machine having, in combination, a tool holder arranged for movement in to different operative positions, a shank tool and a forepart tool carried by said holder and supported in fixed relation to each other, means for vibrating the shank tool in a curved path when it is in operative position and means for vibrating the forepart tool in a rectilinear path when it is in operative position.
26. A burnishing machine having, in combination, a tool holder, a plurality of tools carried by said holder and means including

cam members having rolling engagement with each other for imparting to said holder rapid to-and-fro movements in paths of different curvatures.

5 27. A burnishing machine comprising, in combination, a rigid tool holder, a plurality of tools carried by said holder, means for giving said holder rapid to-and-fro movements in paths of different curvatures and 10 means for yieldingly resisting the pressure of the work against the tools.

28. A burnishing machine having, in combination, a burnishing tool, devices for imparting to said tool rapid to-and-fro movements, mechanism for controlling the path of movement of said tool and means acting through said mechanism for yieldingly resisting the pressure of the work against the tool.

20 29. A burnishing machine comprising, in combination, a burnishing tool, mechanism for imparting to said tool rapid to-and-fro movements, means for causing said tool to move in a predetermined path, the tool being 25 arranged to have a constant relation to said means while in operative position and means for yieldingly resisting the pressure of the work against the tool.

30 30. A burnishing machine comprising a tool holder arranged for movement into different operative positions, mechanism for imparting to said holder rapid to-and-fro movements, means for causing said holder to move in paths of different curvatures 35 when it is in different operative positions, the holder being arranged to have a constant relation to said means while occupying either of its operative positions and means for yieldingly resisting the pressure of the work against the tool holder.

31. A burnishing machine comprising in combination a tool holder movable into different operative positions, means for imparting to said holder rapid to and fro 45 movements and means including a cam having a plurality of cam faces that are brought into operation alternately to change the path of travel of the holder when the holder is shifted from one position to another.

50 32. A burnishing machine having in combination a tool holder, mechanism for imparting to said holder rapid to-and-fro movements and means comprising devices having a plurality of pairs of coöperating 55 cam faces for varying the path of movement of said holder, said means being so constructed and arranged that one pair of cam faces may be thrown out of operative engagement and another pair into operative 60 engagement to change the path of movement of the holder.

33. A burnishing machine comprising, in combination, a plurality of burnishing tools arranged for movement into and out of operative position, mechanism for imparting

to said tools rapid to-and-fro movements, means comprising devices having a plurality of pairs of coöperating cam faces for controlling the path of movement of said tools and means acting automatically when one tool is substituted for another to throw one pair of cam faces out of operative engagement and another pair into operative engagement to cause one tool to move in a different path from the other.

75 34. A burnishing machine comprising, in combination, a rocker frame, a burnishing tool rocking with said frame, said rocker frame having a cam face formed thereon, and a cam bar having a cam face arranged to engage the face on the rocker frame, said cam faces being shaped to cause the tool to move in a predetermined path and means operating through said bar whereby the tool may yield with the pressure of the work.

80 35. A burnishing machine comprising, in combination, a rocker frame, a burnishing tool arranged to rock with said frame, said frame having a cam face formed thereon, a cam bar having a cam face arranged to engage the cam face on the rocker frame, said cam faces being shaped to cause the tool to move in a predetermined path, means for yieldingly holding said faces in engagement with each other, and means whereby said faces may be thrown out of engagement with each other to change the path of travel of the tool.

85 36. A burnishing machine comprising, in combination, a rockshaft having a deep groove formed therein, a rocker frame positioned in said groove, a spring interposed between said frame and the bottom of said groove, a pivoted cam bar positioned above said rockshaft, a spring bearing on said bar, 90 said rocker frame and cam bar each having a cam face formed thereon, the faces being arranged to contact with each other, a tool holder operatively associated with the rocker frame and arranged to be rotated 95 thereon into different operative positions, and a cam plate rotating with said holder and having a thick portion and a thin portion, the thick portion being arranged to engage a second cam face formed on said cam bar and during such engagement to hold the first mentioned cam faces out of engagement with each other.

100 37. A machine of the class described, comprising, in combination, a finger rest or hook, a plurality of tools movable in to and out of operative position, and means whereby said rest or hook is locked against movement when one tool is in operative position and is unlocked and free to move when another tool is in operative position.

105 38. A machine of the class described comprising, in combination, a plurality of tools movable in to and out of operative position, a finger rest and means for automatically

locking said rest against movement or unlocking the same according to the tool that is in operative position.

39. A machine of the class described comprising, in combination, a shank tool and a forepart tool movable in to and out of operative position, a finger rest and means whereby said rest is automatically locked against movement when the forepart tool is in operative position and is automatically unlocked when the shank tool is in operative position.

40. A machine of the class described comprising a movably mounted finger rest, a plurality of movable tools and means controlled by the position of the tools for automatically locking said rest against movement in certain directions.

41. A machine of the class described comprising, in combination, a movably mounted finger hook, a device arranged to lock said hook against movement, a movable tool holder and means moving with said holder for operating said device to lock or unlock the hook.

42. A machine of the class described comprising, in combination, a movably mounted finger hook, a movable tool holder and means operated by the tool holder for successively locking said hook against movement and unlocking the same.

43. A machine of the class described comprising, in combination, a swinging arm, a finger hook carried thereby, a rotatable tool holder, a locking mechanism arranged to lock said arm rigidly against movement and means mounted on the tool holder for operating said locking mechanism to lock or unlock the hook.

44. A machine of the class described comprising, in combination, a movable finger hook, a tool holder movable into different positions and means controlled by said holder for locking said hook against movement or releasing the hook to permit it to move according to the position occupied by the holder.

45. A burnishing machine comprising a movably mounted finger hook, means for locking said hook against movement and means under the control of the workman for operating said locking means to lock or unlock the hook.

46. A burnishing machine comprising a finger hook, a pivoted arm carrying said hook, said arm having an aperture formed

therein with locking shoulders formed in the walls of the aperture, a tilting locking plate projecting through said aperture and arranged to engage said shoulders, a rotatable tool holder, a shank tool and a forepart tool carried by said holder and locking projections provided on the holder and arranged to engage said plate to tilt the plate into engagement with the locking shoulders when the forepart tool is in operative position and to tilt the plate out of locking engagement with said shoulders when the shank tool is in operative position.

47. A burnishing machine comprising a rocker frame, a tool holder rotatably mounted on said frame, a shank tool and a forepart tool carried by said holder, an actuating lever for causing either of said tools to be rotated into or out of operative position, a finger hook, an arm pivotally mounted on said actuating lever and adjustably supporting said finger hook, said arm having an aperture formed therethrough with locking shoulders formed in the walls of the aperture, a locking plate projecting through said aperture, said plate having a cylindrical shank portion received in a correspondingly shaped socket in the actuating lever, and locking projections formed one on each end of said tool holder, one of said projections being arranged when it contacts with said plate to tilt the plate into engagement with the locking shoulders and the other projection being arranged when it contacts with the plate to tilt the plate out of locking engagement with the shoulders.

48. A machine of the class described, comprising in combination, a rocker frame, a tool holder rotatable relatively to said frame but arranged to rock therewith, means for locking said holder against rotation relatively to said frame, an actuating device, a member arranged to engage the tool holder to turn the same, and a second member carried by said device and constructed to engage and move the first member to unlock said holder and thereafter to rotate the holder.

In testimony whereof I have signed my name to this specification in the presence of two subscribing witnesses.

FREDERICK M. FURBER.
